DESIGN FOR A CANDY FIGURE

Willard E. Cook, Shaker Heights, Ohio, assignor to Cook Specialty Company, Cleveland, Ohio,
a corporation of Ohio

Application October 9, 1936, Serial No. 65,226

Term of patent 7 years

To all whom it may concern:

Be it known that I, Willard E. Cook, a citizen of the United States, residing at Shaker Heights,
in the county of Cuyahoga and State of Ohio,
have invented a new, original, and ornamental Design for a Candy Figure, of which the following is a specification, reference being had to the accompanying drawing, forming a part thereof.

In the drawing:

Fig. 1 shows a front elevation of a candy figure showing my new design; and

Fig. 2 shows a side elevation of a candy figure showing my new design.

I claim:

The ornamental design for a candy figure, substantially as shown.

WILLARD E. COOK.
